FURNACE WALL CONSTRUCTION

William W. Barr, Pittsburgh, Pa., and Paul J. Maddox, Evanston, Ill., assignors to Laclede-Christy Company, St. Louis, Mo., a corporation of Missouri

Application January 30, 1953, Serial No. 334,285

7 Claims. (Cl. 72—101)

The present invention relates generally to wall construction for furnaces, and more particularly to a furnace wall construction of individual tiles supported in horizontal tiers in which the metal brackets are entirely outside of the plane of the wall proper.

In brief, the present novel wall construction comprises a plurality of selected variously formed refractory tiles which are supported in tiers by novel brackets. The novel brackets are removably mounted on vertically spaced horizontally disposed supporting members, the brackets on each supporting member being disposed in horizontally spaced relation. Each bracket supports a hanger tile through the medium of bosses, and each hanger tile receives in supported relation on additional bosses a pair of left-hand and right-hand foot tiles cooperatively formed to receive and to support filler tiles. These clusters of hanger supported tiles form a horizontal row, there being vertically spaced horizontal rows of such tiles supported by the hanger tiles. Between the horizontal rows of such aforesaid tiles are additional tiles of selected shape which fill out the present novel wall construction. Insulation is mounted behind the refractories in a manner enclosing very little of the metal work. The wall construction may be repaired, or initially constructed from the outside.

There has long existed a need of a furnace wall construction such as that outlined in the foregoing paragraph. While there are numerous furnace wall formations in both tile and monolithic refractory materials, there has existed the need for a furnace wall of tiered formation in which the metal supports are behind the wall in order to afford protection from the intense heat of the furnace, which will permit the use of a metal in the brackets of lower heat resistance characteristics, and, hence, of lower costs, which may be properly insulated without damage to metal parts, and which may be repaired from the outside.

Therefore, an object of the present invention is to provide a novel furnace wall construction of tiered tile formation in which the metal brackets are disposed entirely rearwardly or outside of the wall, and which is insulated.

Another object is to provide a novel furnace wall construction of tiered tile formation in which a worn or damaged tile may be replaced without the requirement of dismantling the whole wall, and in which such repair may be accomplished from the outside of the furnace.

Another object is to provide a novel furnace wall construction of tiered tile formation which is simple to install and readily maintained.

Other objects and advantages are apparent from the following description taken with the accompanying drawings, in which:

Fig. 1 is a front elevational view of a segment of a furnace wall construction incorporating the concepts of the present invention;

Fig. 2 is an enlarged horizontal segmental cross-sectional view on substantially the line 2—2 of Fig. 1;

Fig. 3 is a vertical cross-sectional segmental view on substantially the line 3—3 of Fig. 2;

2

Fig. 4 is an enlarged vertical cross-sectional view on substantially the line 4—4 of Fig. 1;

Fig. 5 is an isometric view of one tile which may be used to fill in the present novel wall construction;

Fig. 6 is a top plan view of the hanger tile forming part of the present novel wall construction;

Fig. 7 is a side elevational view thereof;

Fig. 8 is an end elevational view thereof;

Fig. 9 is a front elevational view of a novel bracket forming part of the present novel furnace wall construction;

Fig. 10 is a side elevational view thereof;

Fig. 11 is a rear elevational view thereof;

Fig. 12 is an isometric view of a novel filler tile forming part of the present novel furnace wall construction;

Fig. 13 is an isometric view of a novel right-hand foot tile forming part of the present novel furnace wall construction; and

Fig. 14 is an isometric view of a left-hand foot tile forming part of the present novel furnace wall construction.

Referring to the drawings more particularly by reference numerals, 20 indicates generally a furnace wall construction embodying the teachings of the present invention.

25 Broadly, the furnace wall construction 20 includes vertical H-beam supports 22, horizontally disposed and vertically spaced bracket supporting composite members 24 which are supported by the members 22, hanger tile supporting brackets 26 mounted on the members 24, hanger

30 tiles 28 mounted on the brackets 26, adjacently disposed right- and left-hand foot tiles 30 and 32, respectively, hanging on the hanger tiles 28, filler tiles 34 supportingly wedged between each opposed pair of foot tiles 30 and 32, tiles 37 and 38, respectively, disposed beneath the bottom row of tiles 32 and 34, intermediate tiles 39 and 40, respectively, cap tiles 41, and insulation 42. It is to be understood, of course, that the furnace wall construction 20 of Fig. 1 of the drawings is only an illustrative segment of a furnace wall, being all that is required to demonstrate the present invention.

35 The composite bracket supporting members 24 comprise channel members 44 and angle members 45 welded or otherwise secured together as clearly shown in Fig. 4, the composite member 24 being welded or otherwise secured to the vertical supporting members 22.

40 Each hanger tile supporting bracket 26 is preferably of the configuration clearly shown in Figs. 9, 10, and 11, and includes parallel spaced hook arms 48, an angularly disposed base or saddle portion 49, a horizontal foot 50, a vertically disposed foot 51, a vertical fin 52 which supports said feet 50 and 51, a notch 53 in the web 52, and opposed flange portions 54 extending outwardly from the web 52 adjacent a major portion of the notch 53.

45 The hanger tile 28 is preferably of the configuration clearly shown in Figs. 6, 7 and 8 in the drawings, and includes a main base portion 57 from both sides of which and in opposed relation extend a single rearwardly disposed boss 58 and a pair of forwardly disposed bosses 59. Included in the periphery of the main base portion 57 are converging sides 60.

50 The left-hand foot tile 32 is preferably of the configuration shown in the drawings, particularly Figs. 13 and 14, the right-hand foot tile 30 shown in Fig. 13 being the same as the tile 32 except for the hanger tile engaging portion.

55 The tile 32 includes a hanger tile engaging portion 64 having a vertically disposed face 65 in which are spaced wells 66 and an angularly disposed face 67 which is more particularly shown in Fig. 3. Forwardly of the hanger tile portion 64 is a main body portion 68 having a transverse channel 69 in the top face thereof, and a deep notch 70 extending transversely across the bottom face thereof.

60 Fig. 3 is a vertical cross-sectional segmental view on substantially the line 3—3 of Fig. 2;

The right-hand foot tile 30 is like the tile 32 except the

hanger tile portion 64' faces in the opposite direction, hence, the several portions thereof have been marked with the same reference numerals as the tile 32, being primed to distinguish the two tiles.

The filler tile 34 includes a wedge-shaped portion 74 and a forward portion 75, the latter of which has a transverse channel 76 across the upper face thereof and a deep notch 77 across the lower face thereof.

The tiles 37 are of simple rectangular form with a transverse ridge 80 across the top surface thereof (Figs. 1 and 4). The tiles 38 are of the configuration clearly shown in Figs. 4 and 5 and include a transverse channel 81 across the lower face thereof and a pedestal or raised front portion 82.

The tiles 39 are relatively flat and elongated, being of the configuration clearly shown in Figs. 1 and 4, and each including a longitudinal channel 85 along the upper surface thereof and a longitudinal ridge 86 along the lower surface thereof in superposed relation. The tiles 39 are of a length to overlie one group of tiles 30, 32, and 34, as is clear from Fig. 1. The tiles 40 are like the tiles 38 with the exception of including a transverse ridge 87 across the lower face in lieu of the transverse channel across the lower face of the latter. The pedestal portion of the tile 40 is designated 82'. The tiles 41 are flat, rectangular members, as is clearly shown in Figs. 1 and 4. In the illustrative wall segment 20, the tiles 41 rest upon the uppermost tiles 39 and a channel member 90 disposed across the tops of the supports 22.

The insulation 42 is placed between the refractories and the inner flange of the H-beam supports 22, so that only a small portion of the brackets 26 are embedded. Hence, the structure is insulated without damaging the metal brackets.

Like other walls, the furnace wall 20 is normally constructed of the several elements beginning with the bottom layer of tiles 31, after the metal framework is provided. The succeeding layers of tiles are then built upon the tiles already in place. However, it is to be noted that the construction is tiered and that the tiles 37 and 38 carry no weight with the exception of the fact that the latter rest upon the former. Each horizontal row of tiles 30, 32 and 34, which are supported from the respective hanger tiles 28 extending laterally from and supported by the brackets 26, supports four layers of tiles 39 and a layer of tiles 40.

In order to facilitate sectional repair of the wall construction 20, a thick mortar joint 92 is provided between the top of each tile 38 and 40 and the bottom of the tiles 28, 30, 32 and 34, as is obvious from the drawings. Similar vertical joints may be provided if desired.

The present wall construction 20 permits repair from the outside of the furnace, which is highly advantageous when the furnace space is small or it is necessary to perform repairs when the furnace is running. Also, original construction may be accomplished from the outside.

It is to be noted that the brackets 26 are behind the wall 20, and are so located in relation to the tiles that direct impingement of either flame or high heat is completely avoided.

The present tiered construction breaks up the overall expansion and contraction in the over-all wall area, and restricts these forces to the several tiers. In addition, the tiered formation renders repair easily accomplished and localizes the total work required to replace damaged and worn tiles. A further advantage is the distribution of the weight to the several brackets and supporting members which substantially eliminates the possibility of the wall overturning, since the supporting brackets also function as anchors against such overturning. Each bracket firmly engages its supporting member through the medium of the feet 50 and 51 and the notch 53, as is clear from Fig. 4. The flange 54 also contributes to stabilization of each bracket 26. A still further advantage is the insulation feature. In connection with this feature, the

brackets 26 may be spaced further from the refractories, if desired.

It is apparent that there has been provided a wall construction which fulfills the objects and advantages sought therefor.

It is to be understood that the foregoing description and the accompanying drawings have been given by way of illustration and example. It is also to be understood that changes in form of the elements, rearrangement of parts, and substitution of equivalent elements, which will be obvious to those skilled in the art, are contemplated as within the scope of the present invention which is limited only by the claims which follow.

What is claimed is:

15. Wall construction comprising a horizontal supporting member, spaced brackets engaging said member, each bracket including a pair of aligned hook portions and an angularly disposed substantially planar base portion, a hanger tile supported by each bracket including a pair of oppositely extending bosses at one end and an angularly extending end portion adjacent thereto, said bosses being engaged by said hook portions and said angularly extending end portion resting on said base portion, each hanger tile extending laterally of its supporting bracket and having pairs of oppositely extending bosses at the other end thereof, opposed tiles suspended on said pair of bosses, filler tiles supported by and between pairs of suspended tiles, and tiles supported upon said hanger tiles, opposed tiles, and filler tiles.
20. Wall construction comprising a horizontal supporting member, spaced brackets engaging said member, each bracket including a pair of aligned hook portions and an angularly disposed substantially planar base portion, a hanger tile supported by each bracket including a pair of oppositely extending bosses at one end and an angularly extending end portion adjacent thereto, said bosses being engaged by said hook portions and said angularly extending end portion resting on said base portion, each hanger tile extending laterally of its supporting bracket and having pairs of oppositely extending bosses at the other end thereof, opposed tiles suspended on said pair of bosses, filler tiles supported by and between pairs of suspended tiles, and tiles supported upon said hanger tiles, opposed tiles, and filler tiles.
25. Wall construction comprising a horizontal supporting member, spaced brackets engaging said member, each bracket including a pair of aligned hook portions and an angularly disposed substantially planar base portion, a hanger tile supported by each bracket including a pair of oppositely extending bosses at one end and an angularly extending end portion adjacent thereto, said bosses being engaged by said hook portions and said angularly extending end portion resting on said base portion, each hanger tile extending laterally of its supporting bracket and having pairs of oppositely extending bosses at the other end thereof, opposed tiles suspended on said pair of bosses, filler tiles supported by and between pairs of suspended tiles, and tiles supported upon said hanger tiles, opposed tiles, and filler tiles, and insulation supported between said tiles and said brackets.
30. Wall construction comprising a horizontal supporting member, spaced brackets engaging said member, each bracket including a pair of aligned hook portions and an angularly disposed substantially planar base portion, a hanger tile supported by each bracket including a pair of oppositely extending bosses at one end and an angularly extending end portion adjacent thereto, said bosses being engaged by said hook portions and said angularly extending end portion resting on said base portion, each hanger tile extending laterally of its supporting bracket and having pairs of oppositely extending bosses at the other end thereof, opposed tiles suspended on said pair of bosses, filler tiles supported by and between pairs of suspended tiles, and tiles supported upon said hanger tiles, opposed tiles, and filler tiles, and insulation supported between said tiles and said brackets.
35. A portion of a wall construction for furnaces comprising a horizontal supporting member, spaced brackets engaging said member, each bracket including a pair of aligned hook portions and an angularly disposed substantially planar base portion, a hanger tile supported by each bracket including a pair of oppositely extending bosses at one end and an angularly extending end portion adjacent thereto, said bosses being engaged by said hook portions and said angularly extending end portion resting on said base portion, each hanger tile extending laterally of its supporting bracket and having pairs of oppositely extending bosses at the other end thereof, opposed tiles suspended on said pair of bosses, and filler tiles supported by and between pairs of suspended tiles.
40. A portion of a wall construction for furnaces comprising a horizontal supporting member, spaced brackets engaging said member, each bracket including a pair of aligned hook portions and an angularly disposed substantially planar base portion, a hanger tile supported by each bracket including a pair of oppositely extending bosses at one end and an angularly extending end portion adjacent thereto, said bosses being engaged by said hook portions and said angularly extending end portion resting on said base portion, each hanger tile extending laterally of its supporting bracket and having pairs of oppositely extending bosses at the other end thereof, opposed tiles suspended on said pair of bosses, and filler tiles supported by and between pairs of suspended tiles.
45. A portion of a wall construction for furnaces comprising a horizontal supporting member, spaced brackets engaging said member, each bracket including a pair of aligned hook portions and an angularly disposed substantially planar base portion, a hanger tile supported by each bracket including a pair of oppositely extending bosses at one end and an angularly extending end portion adjacent thereto, said bosses being engaged by said hook portions and said angularly extending end portion resting on said base portion, each hanger tile extending laterally of its supporting bracket and having pairs of oppositely extending bosses at the other end thereof, opposed tiles suspended on said pair of bosses, and filler tiles supported by and between pairs of suspended tiles.
50. A portion of a wall construction for furnaces comprising a horizontal supporting member, spaced brackets engaging said member, each bracket including a pair of aligned hook portions and an angularly disposed substantially planar base portion, a hanger tile supported by each bracket including a pair of oppositely extending bosses at one end and an angularly extending end portion adjacent thereto, said bosses being engaged by said hook portions and said angularly extending end portion resting on said base portion, each hanger tile extending laterally of its supporting bracket and having pairs of oppositely extending bosses at the other end thereof, opposed tiles suspended on said pair of bosses, and filler tiles supported by and between pairs of suspended tiles.
55. A portion of a wall construction for furnaces comprising a horizontal supporting member, spaced brackets engaging said member, each bracket including a pair of aligned hook portions and an angularly disposed substantially planar base portion, a hanger tile supported by each bracket including a pair of oppositely extending bosses at one end and an angularly extending end portion adjacent thereto, said bosses being engaged by said hook portions and said angularly extending end portion resting on said base portion, each hanger tile extending laterally of its supporting bracket and having pairs of oppositely extending bosses at the other end thereof, opposed tiles suspended on said pair of bosses, and filler tiles supported by and between pairs of suspended tiles.
60. A portion of a wall construction for furnaces comprising a horizontal supporting member, spaced brackets engaging said member, each bracket including a pair of aligned hook portions and an angularly disposed substantially planar base portion, a hanger tile supported by each bracket including a pair of oppositely extending bosses at one end and an angularly extending end portion adjacent thereto, said bosses being engaged by said hook portions and said angularly extending end portion resting on said base portion, each hanger tile extending laterally of its supporting bracket and having pairs of oppositely extending bosses at the other end thereof, opposed tiles suspended on said pair of bosses, and filler tiles supported by and between pairs of suspended tiles.
65. A portion of a wall construction for furnaces comprising a horizontal supporting member, spaced brackets engaging said member, each bracket including a pair of aligned hook portions and an angularly disposed substantially planar base portion, a hanger tile supported by each bracket including a pair of oppositely extending bosses at one end and an angularly extending end portion adjacent thereto, said bosses being engaged by said hook portions and said angularly extending end portion resting on said base portion, each hanger tile extending laterally of its supporting bracket and having pairs of oppositely extending bosses at the other end thereof, opposed tiles suspended on said pair of bosses, and filler tiles supported by and between pairs of suspended tiles.
70. A portion of a wall construction for furnaces comprising a horizontal supporting member, spaced brackets engaging said member, each bracket including a pair of aligned hook portions and an angularly disposed substantially planar base portion, a hanger tile supported by each bracket including a pair of oppositely extending bosses at one end and an angularly extending end portion adjacent thereto, said bosses being engaged by said hook portions and said angularly extending end portion resting on said base portion, each hanger tile extending laterally of its supporting bracket and having pairs of oppositely extending bosses at the other end thereof, opposed tiles suspended on said pair of bosses, and filler tiles supported by and between pairs of suspended tiles, and insulation supported between said tiles and said brackets.
75. A portion of a wall construction for furnaces comprising a horizontal supporting member, spaced brackets engaging said member, each bracket including a pair of aligned hook portions and an angularly disposed substantially planar base portion, a hanger tile supported by each bracket including a pair of oppositely extending bosses at one end and an angularly extending end portion adjacent thereto, said bosses being engaged by said hook portions and said angularly extending end portion resting on said base portion, each hanger tile extending laterally of its supporting bracket and having pairs of oppositely extending bosses at the other end thereof, opposed tiles suspended on said pair of bosses, and filler tiles supported by and between pairs of suspended tiles, and insulation supported between said tiles and said brackets.

5. Wall construction for furnaces, and the like, comprising a plurality of bracket supporting members, means supporting said members in vertically spaced relation, a plurality of brackets mounted on each member in spaced relation, a hanger tile mounted on each bracket and extending laterally therefrom including oppositely extending pairs of bosses at the portion of the tile remote from the supporting bracket, a pair of opposed left and right-hand tiles suspended from said hanger tile, each suspended tile including a pair of recesses receiving a pair of bosses for support, a filler tile between and supported by each pair of opposed tiles, said opposed tiles and filler tiles forming vertically spaced tile rows, and a plurality of intermediate tiles mounted on each tile row filling the spaces therebetween to complete a solid wall construction.

6. Wall construction for furnaces, and the like, comprising a plurality of bracket supporting members, means supporting said members in vertically spaced relation, a plurality of brackets mounted on each member in spaced relation, a hanger tile mounted on each bracket and extending laterally therefrom including oppositely extending pairs of bosses at the portion of the tile remote from the supporting bracket, a pair of opposed left and right-hand tiles suspended from said hanger tile, each suspended tile including a pair of recesses receiving a pair of bosses for support, a filler tile between and supported by each pair of opposed tiles, each right and left-hand tile including a downwardly divergent side face portion, said side face portions being remote from said hanger tile, each filler tile including opposed downwardly convergent face portions which are disposed adjacent divergent face portions of its supporting suspended tiles, said opposed tiles and filler tiles forming vertically spaced tile rows, and a plurality of intermediate tiles mounted on each tile row filling the spaces therebetween to complete a solid wall construction.

7. Wall construction for furnaces, and the like, comprising a plurality of bracket supporting members, means supporting said members in vertically spaced relation including laterally spaced vertical structural members, 5 a plurality of brackets mounted on each member in spaced relation, a hanger tile mounted on each bracket and extending laterally therefrom including oppositely extending pairs of bosses at the portion of the tile remote from the supporting bracket, a pair of opposed left and right-hand tiles suspended from said hanger tile, each suspended tile including a pair of recesses receiving a pair of bosses for support, a filler tile between and supported by each pair of opposed tiles, each right and left-hand tile including a downwardly divergent side face 10 portion, said side face portions being remote from said hanger tile, each filler tile including opposed downwardly convergent face portions which are disposed adjacent divergent face portions of its supporting suspended tiles, said opposed tiles and filler tiles forming vertically spaced 15 tile rows, and a plurality of intermediate tiles mounted on each tile row filling the spaces therebetween to complete a solid wall construction, said filler tiles being removable from exteriorly of said wall construction.
